(57) **CLAIM**

The ornamental design for a foldable storage rack, as shown and described.

DESCRIPTION

FIG. 1 is a front, top, left side perspective view of a foldable storage rack according to a first embodiment of the present disclosure;

FIG. 2 is a rear, bottom, right side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of a portion indicated with numeric 9 in FIG. 1; and,

FIG. 10 is a perspective view of the foldable storage rack, in which the foldable storage rack is in a folded configuration;

FIG. 11 is a front, top, left side perspective view of a foldable storage rack according to a second embodiment of the present disclosure;

FIG. 12 is a rear, bottom, right side perspective view thereof;

FIG. 13 is a front elevational view thereof;

FIG. 14 is a rear elevational view thereof;

FIG. 15 is a left-side elevational view thereof;

FIG. 16 is a right-side elevational view thereof;

FIG. 17 is a top plan view thereof;

FIG. 18 is a bottom plan view thereof; and,

FIG. 19 is a perspective view of the foldable storage rack, in which the foldable storage rack is in a folded configuration. The broken lines in the drawings depict reference to the enlargements only and form no part of the claimed design.
